UNITED STATES PATENT OFFICE.

ALBERT L. MILLIGAN, OF DALLAS, TEXAS.

ATTACHMENT FOR CARBURETERS.

1,258,696.

Specification of Letters Patent. Patented Mar. 12, 1918.

Application filed July 31, 1916. Serial No. 112,264.

To all whom it may concern:

Be it known that I, ALBERT L. MILLIGAN, a citizen of the United States, residing at Dallas, in the county of Dallas and State of Texas, have invented certain new and useful Improvements in Attachments for Carbureters, of which the following is a specification.

My invention has relation to an attachment for carbureters for automobile engines and in such connection it relates more particularly to the arrangement and construction of an attachment whereby the heated air or vapor accumulating in the upper portion of the radiator of the engine may be conducted to the mixing chamber of the carbureter.

Heretofore several attempts have been made to utilize the heated air or vapor accumulating in the top of radiator by feeding the same to the carbureter but when such means were simple no provision was made to prevent the overflow of water during the filling of the radiator, into the pipe leading the air or vapor to the carbureter. Some devices for preventing the water thus overflowing into the hot air or vapor feed pipe from entering the carbureter have been devised but demanded the use of floats and valves of complicated structure and arrangement.

It is the main object of my invention to provide a means whereby only the hot air or vapor may be sucked into the carbureter, the feed pipe from the hot air chamber of the radiator being provided at its discharge end with an air sealing device in the form of a siphon which will permit the overflow water to be discharged automatically but will prevent the sucking in of external air from the discharge end of the feed pipe to the carbureter.

In carrying out my invention there is provided a main pipe leading from the top of the radiator to the external air. The discharge end of this pipe is provided with a siphon overflow and the hot air feed pipe leading from the main pipe to the carbureter taps the main pipe at a point above the siphon overflow.

The nature and scope of my invention will be more fully understood from the following description taken in connection with the accompanying drawings forming a part hereof, in which—

Figure 1, is a perspective view of an au-

tomobile engine and radiator and of the attachment embodying the main features of my invention.

Fig. 2, is a side elevational view partly in section illustrating the construction and arrangement of the lower or outlet end of the main pipe and of the hot air feed pipe tapping said main pipe and leading to the carbureter.

Fig. 3, is a side elevational view partly in section of the carbureter and of the hot air feed pipe tapping the air intake pipe entering said carbureter.

Fig. 4, is a sectional view showing the top of the radiator and the end of the main pipe entering therein, and

Fig. 5, is a vertical sectional view of a modified form of attachment or siphon seal for the outlet end of the main pipe.

Referring to the drawings 1 represents the radiator and 2 the carbureter of an automobile engine 3. From the top of the radiator 1 preferably within the cap 4 leads the main pipe 5 designed to conduct the hot air or vapor accumulating in the top of the radiator 1 to the air intake 6. This pipe 5 leads to the exterior of the engine and is designed to discharge overflow of water from the radiator to the open air.

To the outlet end of pipe 5 is coupled or otherwise secured a trap 8 of the ordinary siphon type. In Fig. 2, this trap is formed by bending a pipe into substantially double U-shape. The top of the trap 8 is tapped as at 9 and a feed pipe 10 conducts the hot air in main pipe 5 to the air intake 6. The trap 8 is a seal for the lower end of the pipe 5, the water accumulating in the bends of the trap to prevent the air from entering from the exterior of the engine into said pipe 5. When overflow of water from radiator 1 enters the pipe 5, said water will pass through the trap 8 and discharge to the exterior of the engine but said overflow water will not flow into the feed pipe 10 nor into the carbureter 2.

In Fig. 5 a modification is shown in which the trap is formed by boring a solid block or casting 18 and plugging up the unnecessary openings by plugs 19. In this form the feed pipe 10 taps the trap through a hole bored as at 20 in the top of casting 18, and a cork ball 21 inserted in the trap prevents entrance of exterior air to the trap if the water in the trap should evaporate or escape.

Having thus described the nature and objects of my invention what I claim as new and desire to secure by Letters Patent, is—

In a device of the character described, a solid casting bored longitudinally and transversely to form a siphon passage extending through the casting, said transverse bores being plugged at the outer portions of the casting and an intermediate longitudinal bore being also closed at the upper edge of

said casting, in combination with a pipe leading to one longitudinal bore, a pipe leading from another longitudinal bore and a pipe extending transversely of the block and entering the longitudinal bore below the lead-in pipe.

In testimony whereof I have signed my name to this specification.

ALBERT L. MILLIGAN.
